UNITED STATES PATENT OFFICE.

JAMES S. LYNCH, OF BROOKLYN, NEW YORK.

WINDOW-CLEANING CHAIR.

SPECIFICATION forming part of Letters Patent No. 565,764, dated August 11, 1896.

Application filed April 11, 1895. Serial No. 545,363. (No model.)

To all whom it may concern:

Be it known that I, JAMES S. LYNCH, of Brooklyn, in the county of Kings and State of New York, have invented a new and Improved Window-Cleaning Chair, of which the following is a full, clear, and exact description.

My invention relates to a window-cleaning chair, and the object of the invention is to provide a chair for such purposes which will be as simple in its construction as a chair for ordinary use and as readily manipulated; and a further object of the invention is to provide an exceedingly simple and economic locking device for securing the chair in position for use on the outside of the window.

The invention consists in the novel construction and combination of the several parts, as will be hereinafter fully set forth, and pointed out in the claims.

Reference is to be had to the accompanying drawings, forming a part of this specification, in which similar figures and letters of reference indicate corresponding parts in all the views.

Figure 1 is a vertical section through a portion of the window-frame and its sill, illustrating the chair as secured on the sill, the chair being in side elevation; and Fig. 2 is a perspective view of the chair.

In carrying out the invention the chair consists of the bottom A and the back B. The front edge of the bottom is straight, and preferably the entire bottom is of somewhat semispherical shape in outline, (although it may be given other contour,) and the back B is made of corresponding shape. The back may be of any character, that shown in the drawings comprising a series of vertical bars 10 and a rail 11, connecting all the bars at the top.

The back of the chair is provided with a front vertical bar 12, round in cross-section, located at each side, these front bars being secured to the ends of the rail 11, and the aforesaid front bars are of metal, and are preferably each provided with a stop 13, in the nature of a shoulder, at a predetermined point in its length; but the stop may be omitted if desired.

In connection with the body of the chair clamping devices C are employed. These de-

vices are two in number and are of like construction, each comprising an angled bar consisting of a horizontal member 14 and a vertical member 15, the latter being at the inner end of the horizontal member, the outer end of the said member terminating in an eye 14^a, through which one of the front metal bars 12 of the chair-body passes. This angle-bracket is therefore capable of sliding freely on or of swinging on the front bar 12, and at the lower end of the vertical member 15 of the angle-bracket an eye 15^a is formed threaded to receive a horizontal adjusting-screw 16, having a head at its outer end, preferably having attached to it or being covered by a cushion 17.

In operation the chair is placed with the bottom of its body on the outside window-sill 70 of the window-frame, the front straight portion of the said bottom bearing against the outer riser of the lower sill of the window-frame proper, as shown in Fig. 1, the brackets of the clamping devices being immediately slid up on their supports until their vertical members are in front of the wall-space below the inside edge of the window-sill. They are then permitted to drop to an engagement with the stop 13, and the adjusting-screws 16 80 are manipulated until their cushioned ends firmly bind against the wall-surface beneath the inside window-sill. The brackets and the clamping devices are made of a size to readily receive any window-frame, the difference in width being provided for by the manipulation of the adjusting-screws 16. This device is exceedingly simple, durable, and economic, and when attached to a window provides a perfectly safe seat for a person when cleaning a window.

By the construction of the device as above described it will be seen that when the improved chair is not required for use the clamping devices C may be slid up on the vertical bars 12 of the chair, and when slid up may be folded inwardly inside the back of the chair, so that the device will occupy comparatively little space.

Having thus described my invention, I claim as new and desire to secure by Letters Patent—

1. In a window-cleaning chair, the combination of a back and seat having at its for-

ward part vertical bars, and clamping devices having their outer ends provided with means to engage the window-sill, said clamping devices having their inner ends arranged to slide on the vertical bars and being adapted when slid upward to be folded within the back of the chair, substantially as set forth.

2. In a window-cleaning chair or the like, the combination of a seat, a back comprising a series of vertical bars secured at their lower ends to the upper part of the seat, and a curved rail connecting said vertical bars at their upper ends, clamping devices com-

prising angular bars arranged to slide and turn on the vertical bars of the back, and set-screws carried in the outer ends of the angular bars and arranged to engage the inner side of a window-sill, said clamping devices being arranged to turn on the vertical bars of the back whereby they may be folded within said back, substantially as set forth.
